UNITED STATES PATENT OFFICE.

EDGAR T. MEAKIN, OF BERKELEY, CALIFORNIA.

CONTINUOUS PRESS.

1,421,282.

Specification of Letters Patent. Patented June 27, 1922.

Original application filed January 24, 1918, Serial No. 213,452. Divided and this application filed October 29, 1918. Serial No. 260,142.

To all whom it may concern:

Be it known that I, EDGAR T. MEAKIN, citizen of the United States, and a resident of Berkeley, county of Alameda and State 5 of California, have invented a certain new and useful Continuous Press, of which the following is a specification.

This application is a division of application Serial Number 213,452, filed in the 10 United States Patent Office, January 24, 1918.

My invention relates to a press for extracting liquids from substances containing the same, and one of the objects of the invention 15 is to provide a press in which means are arranged for removing the residue from the press after the liquids have been extracted.

Another object of the invention is to provide 20 a press of the character described having means for varying the degree of pressure to which the material in the press is subjected.

Another object of the invention is to provide 25 a press in which means are included for varying the longitudinal relation of the feed and pressure screw.

Another object of the invention is to provide 30 a press in which the feed and pressure screws are provided with an improved form of flights or threads.

The invention possesses other features of advantage, some of which, with the foregoing, will be set forth in the following description 35 of the preferred form of my invention which is illustrated in the drawings accompanying, and forming part of the specification. It is to be understood that I do not limit myself to the showing made 40 by the said drawings and description, as I may adopt variations of the preferred form within the scope of my invention as set forth in the claims.

Referring to the drawings: 45 Figure 1 is a plan view of the press of my invention.

Figure 2 is a vertical sectional view of the press. The plane of section is indicated by the line 2—2 of Fig. 1.

The press of my invention is particularly suited for use in connection with the making 50 of fish meal as pointed out at length in my co-pending application above referred to; also in extracting the juice from pine-

apples, lemons and other fruits and for 55 analogous uses. Broadly it comprises a foraminated cylindrical casing in which a feed screw of improved pattern propels the material under treatment to a pressure screw, which squeezes the material to substantial dryness. Means are provided for 60 positively insuring the feed of the material to the pressure screw, for permitting the free liquids to drain from the material during its progress to the pressure screw, for 65 extracting the pressed material from the casing, and for regulating the pressure exerted upon the material. Means are also provided for permitting and effecting longitudinal adjustment between the feed and 70 pressure screws.

A cylindrical casing 2 is suitably held in frames 3 which in turn are mounted upon supporting beams 4. Preferably the casing is made in two parts, the portion 2^a being 75 provided with an intake hopper 6 into which the material to be pressed falls from any suitable source. The casing is provided with a multiplicity of closely spaced small apertures 7 through which the liquids from 80 the material drain. It is frequently desirable to separate the free liquids from those pressed from the material and therefore a catch basin 8 drained by the pipe 9 is disposed below that portion of the casing 2 in 85 which the feed screw generally designated by the character 11 lies, and a catch basin 12 drained by the pipe 13 is disposed below that portion of the casing in which the pressure screw, generally designated by the 90 character 14, and the extractor screw generally designated by the character 15 lie.

The feed screw 11 comprises a hollow shaft 16, the end 16^a of which is journaled in the bearing 17 disposed in the adjacent frame 3, and upon which, threads or flights 18 are helically disposed. The screw 11 also rotates upon the shaft 19 disposed longitudinally through the press casing 2 and supported in suitable bearings arranged in 95 the frames 20 and 21. A gear 22 keyed upon the outer end of the hollow shaft of the screw meshes with pinion 23 on jack shaft 34 which is driven by tight pulley 26 connected to any desired source of power. 100 A feeder wheel 27 is mounted at the entrance of the main portion of the press casing 2, its arms projecting into the spaces 105

between the flights 18 of the screw. The feeder wheel prevents the packing of material between the flights and insures its forward movement toward the pressure screw.

5 The pressure screw 14 comprises a conical hollow shaft 28 fixedly secured to the shaft 19 upon which the feed screw 11 rotates. Helically disposed on the shaft 28 are 10 threads or flights 29 similar to threads 18 on shaft 16. One end 28^a of the shaft 28 is cylindrical in form and without threads which are arranged only on the main or conically formed portion. The flange 30 15 supports the cylindrical end of the hollow shaft upon the shaft 19. The hollow shaft extends preferably to adjacent the end of the casing 2. The shaft 19 is rotated by gear 31 in mesh with pinion 32 fixed on 20 the jack shaft 24. The pinion is relatively wider than gear 31 to permit of longitudinal movement of the shaft 19, and the end 28^b of the conical shaft 28 is recessed to fit over the adjacent end of shaft 16 to 25 provide a slip joint therewith during longitudinal adjustment of the shaft 19 and pressure screw relative to the feed screw. This longitudinal adjustment is secured by mounting the end of the shaft 19 in relatively long bearing boxes 33 and 34 to permit 30 of longitudinal or axial movement therein. The outer ends of the boxes are closed and a cap screw 36 provided with a lock nut is threaded through the end wall of each 35 box, and impinges upon the bearing disc 37 disposed between the ends of the screw and shaft. By adjustment of the cap screw 36, the shaft 19 carrying the pressure screw may be moved axially to and retained in 40 the desired position. With material having a high percentage of liquid, the pressure screw is adjusted relatively close to the feed screw, but is spaced farther from the screw with increase in the solid content of 45 the material. The feed and pressure screws are thus relatively adjustable in accordance with the proportion of liquid and solid matter in the material to be treated. This feature enables the operator to adjust the press 50 to operate on any given material at the greatest efficiency for that material. Preferably the speed of rotation of the pressure screw 14 is higher than the speed of the feed screw 11.

55 In the usual type of flight or thread found in screw conveyors the tendency of the material is to crowd to the outer edge of the flight resulting in wearing the forward edges 38 away. A rounded forward 60 edge tends to pack the material against the casing and materially reduces the efficiency of the device. In order to avoid this fault, I form the flights on the screws 11 and 14 of the press with a forward rake or slant 65 sufficient to overcome the outward movement

of the material to the outer edge of the flight. This shape of flight keeps the material working toward the axis of the screw and eliminates the objectionable wear referred to. Figure 2 of the drawings clearly 70 shows the forward rake or slant of the spiral flights relative to the axis of the screw.

An extractor screw is provided for extracting the pressed material from the end 75 of the casing, and this screw also acts as an auxiliary pressure screw, and is adjustable longitudinally in the end of the casing to regulate the maximum degree of pressure to which it is desired to subject the material. 80 The extractor screw, which from one view point may be considered as an adjustable extension of the pressure screw, comprises a conical sleeve 41, lying partly within and partly without the press casing 2. One end 85 of the casing 41 is open and forms a slip fit with the cylindrical end 28^a of the pressure screw 14. The other end of the sleeve is formed integral with the hub 42 slidable upon the shaft 19, but fixed for rotation 90 therewith by means of a spline or key 43. The conical surface of the extractor is provided with flights 44 of the same description as the flights 18 and 29 and of the same diameter.

95 It will be noted that axial adjustment of the extractor screw upon the end of the pressure screw, alters the size of the annular outlet between the press casing 2 and the extractor screw through which the material 100 is discharged by the action of the flight 44. With the extractor moved to the farthest inward position, the outlet is smallest and the material is subjected to the maximum pressure before being discharged from the 105 press. With the extractor moved outwardly, the outlet is enlarged and the material is therefore discharged under a lower pressure. The pressure to which the material in the press is subjected is therefore controllable by the axial adjustment of the extractor screw.

110 Means are provided for manually adjusting the position of the extractor screw longitudinally of the shaft 19 and of the press casing 2. A portion of the shaft between the press casing and the bearing 34 is provided with threads 46, and a sleeve 47 is threaded thereon, which is connected to the hub 42 by the split sleeve 48 having flanges 115 49 in annular grooves in both sleeve and hub. The split sleeve is held in engagement with the sleeve and hub by the lock ring 51 forming a drive fit therewith. The sleeve 47 is thus rotatable relative to the hub 42, but movable axially therewith. The sleeve is provided with sockets 52 adapted to receive the end of a bar or handle to facilitate the easy turning thereof and by rotating the sleeve the extractor screw is moved 120 125 130

to the desired position. A lock nut 53 is also mounted on the shaft to secure the sleeve in the adjusted position.

In order to facilitate the assembling of the press and also the removal of the screws from the press casing, the bearing 34 is preferably arranged in a plate 54 removably connected by means of cap screws 56 with the supporting frame 21. The aperture in the frame closed by the plate 54 is larger than the diameter of the screws so that they may be withdrawn from the press casing through the plate 21 without disturbing the tie rods 57 passing through the frames or other parts.

I claim:

1. In a press, a casing, a pressure screw in said casing, an extractor screw in the end of said casing, and means for axially adjusting said extractor screw relative to the end of said casing.

2. In a press, a casing, a pressure screw in said casing, a conical extractor screw in the end of said casing, and means for axially adjusting said extractor screw relative to the end of said casing.

3. In a press, a casing, a shaft disposed longitudinally in said casing, a pressure screw in said casing rotatable with said shaft, and an extractor screw arranged in the end of said casing, said extractor screw being rotatable with said shaft and axially adjustable thereon.

4. In a press, a casing, a pressure screw in said casing comprising a conical shaft having threads arranged thereon, an extractor screw in the end of said casing comprising a hollow conical sleeve having threads arranged thereon, said extractor sleeve containing the end of said pressure screw, and means for axially adjusting said extractor screw relative to the end of said casing.

5. In a press, a casing, and a pressure screw in said casing having an axially adjustable conical end adapted to extend from the end of said casing.

6. In a press, a foraminated cylindrical casing, and a pressure screw in said casing having an axially adjustable conical end adapted to extend from the end of said casing.

7. In a press, a foraminated cylindrical casing, a pressure screw in said casing having an axially adjustable conical end adapted to extend from the end of said casing, means for adjusting said conical end relative to the end of said casing, and a feed screw for conveying material to said pressure screw.

8. In a press, a foraminated cylindrical casing, a pressure screw in said casing having an axially adjustable conical end adapted to extend from the end of said casing, means for adjusting said conical end relative to the end of said casing, a feed screw

in said casing for conveying material to said pressure screw, and means for rotating said feed and pressure screws at different speeds.

9. In a press, a casing, a pressure screw 70 in said casing, a conical extractor screw in the end of said casing, a feed screw in said casing for conveying material to said pressure screw, and means for axially adjusting said extractor screw relative to the end of 75 said casing.

10. In a press, comprising a casing, a pressure screw in said casing, a feed screw for feeding material to said pressure screw, and means for revolving said feed and pres- 80 sure screws at different speeds.

11. A press, comprising a casing, a pres- 85 sure screw in said casing, a feed screw for feeding material to said pressure screw, and means for adjusting the relative positions of said screws longitudinally.

12. A press comprising a casing, a pres- 90 sure screw in said casing, a feed screw for feeding material to said pressure screw, means for revolving said feed and pressure screws at different speeds, and means for varying their relative positions longitudinally.

13. A press comprising a casing, a pres- 95 sure screw in said casing, a feed screw in said casing for feeding material to said pressure screw, and means co-operating with said feed screw for positively insuring the feeding of material thereby.

14. In a press, a foraminated cylindrical 100 casing, a pressure screw in said casing having an axially adjustable conical end adapted to extend from the end of said casing, means for adjusting said conical end relative to the end of said casing, a feed screw 105 in said casing for conveying material to said pressure screw, and a feeder wheel co-operating with said feed screw.

15. In a press, a foraminated cylindrical 110 casing, a pressure screw in said casing, hav- ing an axially adjustable conical end adapt- ed to extend from the end of said casing, means for adjusting said conical end relative to the end of said casing, and a feed screw for conveying material to said pres- 115 sure screw, said feed and pressure screws being relatively axially adjustable.

16. A press comprising a foraminated cy- 120 lindrical casing, a pressure screw in one end of said casing, a feed screw in the other end of said casing, means for collecting the free liquids draining through said casing from said feed screw, and means for collecting the extracted liquids draining through said casing from said pressure screw.

17. In a press, a pressure screw compris- ing a conical body having threads arranged thereon and being adjustable in length.

18. In a press, a casing, a pressure screw 130 in said casing comprising a conical body

- 1 having threads arranged thereon, and means for longitudinally adjusting said pressure screw relative to the end of said casing whereby the annular space between 5 the casing and the screw is varied.
19. In a press, a casing, a shaft in said casing, a pressure screw fixed on said shaft, a feed screw rotatable on said shaft, means for rotating said pressure and feed screws 10 at different speeds, and means for longitudinally adjusting said shaft to vary the position of said pressure screw relative to said feed screw.
20. In a press, a casing, a shaft in said 15 casing, a pressure screw and a feed screw arranged on said shaft in said casing, one of said screws being fixed and one being rotatable on said shaft, means for rotating the shaft and fixed screw, means for rotating 20 the rotatable screw at a different speed, and means for longitudinally adjusting the shaft.
21. In a press, a casing, a shaft in said 25 casing, a pressure screw in said casing comprising two parts relatively longitudinally adjustable and fixed for rotation with said
- shaft, a feed screw in said casing rotatable upon said shaft, means for rotating said shaft and said feed screw at different speeds, and means for longitudinally adjusting said 30 shaft to vary the relative longitudinal positions of said feed and pressure screws.
22. In a press, a casing, a shaft in said casing, a hollow conical shaft terminating in a cylindrical portion and fixed on said 35 first shaft, threads disposed on the conical surface of said hollow shaft, a hollow conical sleeve enclosing the cylindrical end of said hollow shaft and fixed for rotation with said first shaft and longitudinally slidable 40 thereon, threads disposed on said sleeve, and means for moving said sleeve longitudinally on said first shaft out, and cylindrical portion of said hollow shaft to vary the area of the discharge opening from said casing. 45
- In testimony whereof, I have hereunto set my hand at San Francisco, California, this 19th day of October, 1918.

EDGAR T. MEAKIN.
